UNITED STATES PATENT OFFICE.

ADELBERT F. FILER, OF BIRMINGHAM, ALABAMA, ASSIGNOR TO H. H. BRYANS, TRUSTEE, OF BIRMINGHAM, ALABAMA.

DESIGN FOR AN AUTOMOBILE RADIATOR-CAP ORNAMENT.

Application filed October 25, 1927. Serial No. 23,882. Term of patent 3½ years.

To all whom it may concern:

Be it known that I, ADELBERT F. FILER, a citizen of the United States of America, residing at Birmingham, in the county of Jefferson and State of Alabama, have invented a new, original, and ornamental Design for an Automobile Radiator-Cap Ornament, of which the following is a specification, reference being had to the accompanying drawing, forming a part thereof.

In the drawings—

Fig. 1 is a front view; and

Fig. 2 is a side view of the device.

I claim:

The ornamental design for an automobile radiator cap ornament substantially as shown.

In testimony whereof I ADELBERT F. FILER, affix my signature.

ADELBERT F. FILER.
